UNITED STATES PATENT OFFICE.

ARTHUR GREEN, OF ATLANTA, GEORGIA.

DESIGN FOR A CONE FOR ROLL-PAPER.

SPECIFICATION forming part of Design No. 29,264, dated August 23, 1898.

Application filed July 13, 1898. Serial No. 685,876. Term of patent 14 years.

To all whom it may concern:

Be it known that I, ARTHUR GREEN, a citizen of the United States of America, and a resident of Atlanta, in the county of Fulton and State of Georgia, have invented and produced a new and useful Design for a Cone for Roll-Paper; and I do hereby declare the following to be a clear, full, and exact description of the same, reference being had to the accompanying drawings, and to letters of reference marked thereon, which form a part of this specification.

This device relates to cones used for forming in the ends of rolls of paper or the like journals whereon the said roll may rotate.

The invention is illustrated in the accompanying drawings as follows:

Figure 1 is an end view of the device. Fig. 2 is a view of the inner end, showing the ribs in perspective. Fig. 3 is a side elevation of the device. Fig. 4 is an axial section.

In the figures like reference characters are uniformly employed in the designation of corresponding elements of construction.

This device consists of a short tubular cone

a, tapering on its outer side and its bore being substantially cylindrical. Projecting into the bore at the large end of the cone is an annular flange *b*, which strengthens the cone at that end and gives it a broad finished appearance.

c are ribs on the periphery of the cone, lying longitudinally thereof, their outer edges forming, collectively, the conical portion of the device. The smaller end or point of the cone is substantially smooth on its outer surface as the cone is entered thereby, and its point is slightly smaller than the hole in the roll of paper.

Having thus described my invention, what I claim as new, and desire to secure by Letters Patent, is—

The design for a cone for roll-paper substantially as herein described.

In testimony whereof I hereunto affix my signature in presence of two witnesses.

ARTHUR GREEN.
